UNITED STATES PATENT OFFICE.

FRANK HUMPHRIS, OF PARKSTONE, DORSET, ENGLAND.

JOINING OR AFFIXING PERFORATED OR EXPANDED SHEET METAL.

Application filed April 28, 1927, Serial No. 187,327, and in Great Britain August 24, 1926.

This invention consists of improvements in joining or affixing perforated or expanded sheet metal by providing means which are integral with such sheet metal whereby two or more sheets thereof can be joined together, or whereby one or more sheets thereof can be affixed to either studs, joists, rafters, girders or any other suitable supports without the use of nails, screws, staples, bolts, rivets or the like devices as ordinarily employed for such purposes.

To carry this invention into effect two or more so-called margins or selvedges of the said perforated or expanded sheet metal near the contour edges thereof are so slit or cut as to provide each margin or selvedge with one or more rows of either tongues or so-called spike-like projections integral therewith having either blunt or sharp extremities, which tongues or spike-like projections are sheared and so bent that they project at right angles to the plane of such sheet metal and leave as a result of their being formed in the said margins or selvedges apertures or openings through which the tongues or spike-like projections, produced in a like manner and integral with any other like margin or selvedge of any other sheet or piece of perforated or expanded-metal, are passed, curled, folded or bent over in such manner as to form clinches which serve as securing means.

For affixing the margins or selvedges of the said perforated or expanded sheet-metal to studs, timber or other material, tongues or spike-like projections having sharp extremities are advantageously employed, as these more easily enter the timber or other material.

Each sheet or piece of perforated or expanded metal joined to another according to this invention is made secure by bending into a clinch each tongue or spike-like projection integral therewith after it has been passed through one of the apertures or openings in the margin or selvedge of another piece or sheet of perforated or expanded metal.

The said apertures or openings are the result of shearing the said margins or selvedges to form tongues or spike-like projections therefrom.

All the ends of these tongues or spike-like projections integral with one margin or selvedge of one piece or sheet of expanded or perforated metal which is joined to another

like piece or sheet are bent over in a direction the reverse to that in which the ends of the tongues or spike-like projections integral with another margin or selvedge of another piece or sheet of perforated or expanded metal joined thereto are bent.

The said tongues or spike-like projections and the apertures or openings are of any length, breadth or form, but for giving a more clear understanding the invention will now be described with reference to the accompanying drawings. It is to be understood however that the illustrations are given merely by way of example.

In these drawings:

Figure 1 is a view of a piece of a sheet of perforated metal having in the margin or selvedge thereof sharp spike-like tongues or projections which are formed by slitting the said sheet and by bending out the said tongues.

Figure 2 is a sectional view on the line A—B of Figure 1.

Figure 3 is a view showing two pieces of perforated metal with one margin or selvedge of one piece placed over the margin or selvedge of the other piece and with blunt tongue-like projections integral with one margin or selvedge passed through the apertures or openings resulting from the bending out of the tongue like projections integral with other margin or selvedge. Some of the tongues are illustrated before they are clinched by being bent over and some of the tongues are illustrated after they are bent over and clinched around the edges of the apertures or openings in each of the two margins or selvedges.

Figure 4 is a sectional view on the line C—D of Figure 3.

Figure 5 is a view showing two pieces of expanded metal having margins or selvedges which are joined and secured in a manner like that shown in Figure 3 of the drawings.

Figure 6 is a sectional view on the line E—F of Figure 5, and illustrates some of the tongues before and some after they have been bent over to form clinches.

Figure 7 is a view of a piece of a sheet of perforated metal having two rows of tongues or spike-like projections provided in each of the two margins or selvedges thereof.

Figure 8 is a sectional view on the line G—H of Figure 7, showing how the tongues

or spike-like projections are bent out from the margins or selvedges of a sheet of perforated metal.

Figure 9 is a view of a piece of a sheet of expanded metal having two margins or selvedges in which sharp spike-like tongues or projections are provided.

Figure 10 is a sectional view on the line K—L of Figure 9, showing how the spike-like tongues or projections are bent out from the margins or selvedges of a sheet of expanded metal.

Like letters of reference refer to like parts throughout the drawings.

15 In joining or affixing perforated or expanded metal having margins or selvedges *a* integral therewith there is provided according to this invention, integral with each margin or selvedge thereof, one or more rows 20 of tongue-like projections *b* which are produced as the result of slitting the said margin or selvedge *a*; each of the tongue-like projections *b* integral with each piece of perforated or expanded metal are employed in 25 the joining of two pieces of perforated or expanded metal together and to enable this to be accomplished each of the apertures or openings *c* in one margin or selvedge *a* accommodates one of the tongue-like projections 30 *b* integral with the other margin or selvedge *a* of two pieces of perforated or expanded metal which have been joined together.

Each tongue or spike-like projection *b* is 35 bent over or around the parts *c* local to each aperture or opening *c*.

40 Figures 1, 2, 7, 8, 9 and 10 of the drawings illustrate tongues or spike-like projections *b* having sharp extremities *b*¹ which easily enter timber or other material and serve in substitution of nails, staples, screws or the like, or the said spike-like projections *b* integral with any margin or selvedge *a* are folded over to form clinches after they have been 45 passed through the apertures or openings *c* formed in any other margin or selvedge *a* as illustrated in Figures 3, 4, 5 and 6 of the drawings which show blunt extremities *b*² on the said tongues *b*.

50 When joining two margins or selvedges *a* together one being integral with a piece of perforated metal and one being integral with a piece of expanded metal, or when joining two margins or selvedges *a* together of the same kind, e. g. perforated or expanded metal, then the tongue-like projections *b* integral with each such margin or selvedge *a* being joined are so positioned that those integral with one margin or selvedge *a* project in a 55 direction the reverse to that in which the tongues or spike-like projections *b* integral with the other margin or selvedge *a* being joined, project, as shown on the left-hand side of Figures 4 and 6 of the drawings, 60 which also illustrate on the right-hand side

thereof how, after the said tongues or spike-like projections *b* have been passed through the apertures or openings *c* they are each bent over or clinched around a part *c*¹ of such margin or selvedge *a* with which they are not integral, as shown in Figures 3, 4, 5 and 6 of the drawings.

Each said tongue or spike-like projection *b* is clinched over one said part *c*¹ in any known manner and after this is done each 75 tongue or spike-like projection *b* serves in substitution of a rivet, bolt or the like in the joining of pieces or sheets of perforated or expanded metal together.

It will be obvious that any number of 80 sheets or pieces of perforated or expanded metal each having integral with the margins or selvedges *a* thereof tongues or spike-like projections such as *b*, and also apertures or openings such as *c*, provided in each selvedge 85 *a* thereof, can be joined together by the means hereinbefore described, and such means and also the use of tongues or spike-like projections such as *b* which are turned over to form a clinch on a part such as *c*¹ of another selvedge such as *a* as illustrated on the right-hand side of Figures 4 and 6 of the drawings, or the use of tongues or spike-like projections *b* as illustrated in Figures 1, 2, 7, 8, 9 and 10 of the drawings for affixing perforated or expanded metal to timber or other materials is intended to be included in this 95 invention.

There are optionally provided according 100 to this invention two or more rows or sets of 100 tongues or spike-like projections such as *b* integral with, and apertures or openings such as *c* in any one margin or selvedge *a* employed in joining together two pieces of perforated or expanded-metal or in affixing perforated or expanded-metal to timber or other material, and an example showing two rows or sets 105 of tongues or spike-like projections *b* is illustrated in Figures 7 and 8 of the drawings and such multi-row arrangements of tongues or spike-like projections *b* and apertures or 110 openings *c* is intended to be included in the scope of this invention.

I claim:

1. A built up sheet metal structure comprising two overlapped metal sheets, each of which has a row of equally spaced tongues bent out of the sheet about lines at right angles to the edge of the sheet, the spacing of the tongues being alike for both sheets, one of the sheets being reversed and having its tongues extended through the apertures left in the other sheet by the formation of the tongues in the latter the tongues of said sheets being bent over the opposite face of the latter sheet. 115

2. As an article of manufacture, a sheet of metal having a plain border, and tongues having their edges parallel to each other for a part of their length, said tongues being 120 equally spaced apart and bent out of the bor- 130

der about lines at right angles to the edge of the sheet.

3. A built up sheet metal structure comprising two overlapped sheets of metal having similar spaced apertures in alignment near the edges thereof and tongues resulting from the formation of said apertures having their edges parallel to one another for part of their

length, the tongues of one sheet extending through apertures in the overlapped part of the other sheet and the tongues of one sheet being bent in the opposite direction to the tongues of the other sheet to secure said sheets together. ¹⁰

FRANK HUMPHRIS.
